UNITED STATES PATENT OFFICE

HENRY BAILLET BRUCKNER, OF JERSEY CITY, NEW JERSEY

DESIGN FOR A BERET CAP

Application filed June 25, 1930. Serial No. 36,172. Term of patent 3½ years.

To all whom it may concern:

Be it known that I, HENRY BAILLET BRUCKNER, a citizen of the United States, residing at Jersey City, in the county of Hudson and State of New Jersey, have invented a new, original, and ornamental Design for Beret Cap, of which the following is a specification, reference being had to the accompanying drawing, forming part thereof.

I claim:

The ornamental design for a beret cap, as shown and described.

HENRY BAILLET BRUCKNER.
